CLAIM

The ornamental design for a tissue dispenser, as shown and described.

DESCRIPTION

FIG. 1 is a perspective view of a tissue container showing my new design;

FIG. 2 is a rear elevational view thereof, shown in a closed position;

FIG. 3 is a left side elevational view thereof, shown in a closed position;

FIG. 4 is a right side elevational view thereof, shown in a closed position;

FIG. 5 is a top plan view thereof, shown in a closed position;

FIG. 6 is a bottom plan view thereof; and

FIG. 7 is a front elevational view thereof, shown in a closed position.

The broken-line depiction of a tissue in FIG. 1 is shown for illustrative purposes only and forms no part of the claimed design.

FIG. 1

FIG. 2

FIG. 3

FIG. 4

FIG. 5

FIG. 7
